UNITED STATES PATENT OFFICE.

THOMAS W. VARLEY, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRICAL MEASURING INSTRUMENT.

1,181,270.

Specification of Letters Patent.

Patented May 2, 1916.

Application filed March 20, 1911. Serial No. 615,553.

To all whom it may concern:

Be it known that I, THOMAS W. VARLEY, a citizen of the United States, and a resident of Pittsburgh, in the county of Allegheny and State of Pennsylvania, have invented a new and useful Improvement in Electrical Measuring Instruments, of which the following is a specification.

My invention relates to an improvement in electrical measuring instruments of that type wherein advantage is taken of a substantially constant magnetic field in combination with stationary and movable coils so disposed that a current passing through the stationary coil will shift or distort the lines of force of the magnet in such manner that they will cause a torque on the movable coil, the function of the stationary coil being simply to so shift the lines of force in the magnetic field and not necessarily to create the magnetic field itself, as in the ordinary electro-dynamometer; and the object of the invention is to provide a device of the character described having a high degree of accuracy in operation because of effective compensation for friction and in which there is substantially no liability to side thrust of the movable member because of the use of a double two-pole armature in a two-pole field, both the armature and the field being provided with special windings.

In the following, I have described, with reference to the accompanying drawings, a structure illustrating one embodiment of my invention, together with certain modifications of parts, the features thereof being more fully pointed out hereinafter in the claims.

In the drawings, Figure 1 is a front elevation, partly in section and partly diagrammatic, of a structure designed to be used as a watt hour meter. Fig. 2 is a transverse sectional view along the line A—B of Fig. 1. Fig. 3 is a perspective view showing the pole faces on one side of the magnet, other parts being removed or broken away. Fig. 4 is a diagrammatic view illustrating the connections. Fig. 5 is a detail view of the armature cup showing one form of winding. Fig.

6 illustrates a modification of the armature 50 cup and winding. Fig. 7 is a plan view of a modification of the armature core, and Fig. 8 is a diagrammatic view of a modification of the circuits of the device.

Similar numerals of reference indicate 55 similar parts throughout the several views.

1 represents a substantially constant magnet here shown as a permanent horse-shoe magnet having pole pieces 2 and 3 that are respectively provided with slots 4 and 5 to 60 form polar faces 6 and 7, and 8 and 9.

10 indicates an auxiliary potential winding that is disposed around the polar faces in series-connected coils and is adapted to reversely magnetize the respective faces of 65 each magnet pole piece.

11 indicates one of the load windings that is disposed around the two polar faces at one side in series connected coils, and 12 indicates the other load winding that is disposed around the two polar faces at the other side in series-connected coils, the respective load windings being adapted to reversely magnetize the pole faces around which they are disposed. The potential 70 windings upon one magnet pole are also connected in opposition to the corresponding 75 load windings.

13 is a support, preferably made of non-magnetic material and itself in turn supported in any convenient manner, not shown. Support 13 carries a tube 14, preferably of non-magnetic material, that serves to support a core 15 of magnetic material.

16 is a screw in the bottom of tube 14 that 80 constitutes a support for a shaft 17 having suitable bearings—only one of which is shown—and carrying the armature cup 18; vertical or longitudinal adjustment of the armature with respect to the field poles being effected by means of the screw. Shaft 85 90 17 also carries the commutator member 19 to coöperate with brushes 20, 21, and a pinion 22 to drive any suitable indicating or registering mechanism (not shown).

23 indicates the armature winding carried by armature cup 18, the winding and cup, together, constituting the movable element.

24, 24 indicate the generators here shown in duplicate, as the form of connection shown is that of a three-wire system.

25 indicates the load, 26 and 27 the mains 5 and 28 the neutral wire.

29 indicates the load shunt on one side of the system and 30 the load shunt on the other side of the system.

31 indicates an adjustable resistance across 10 the potential winding on one side of the magnetic circuit.

32 and 33 indicate adjustable resistances in the circuits of the load windings on the respective sides of the system.

15 34 is an adjustable resistance in the potential circuit of the instrument, which includes the winding 23 of the armature cup 18, as the main potential winding, in addition to the winding 10.

20 The winding of the armature is illustrated more particularly in Figs. 5 and 6, both of which show a two-pole closed circuit winding. In Fig. 5, the winding is shown as extending downward vertically for approximately one half of the armature length, then circumferentially to a point diametrically opposite, then downward vertically the length of the remainder of the armature, then circumferentially on the same side of 30 the armature, as before, to a point diametrically opposite, then upward vertically approximately one half of the armature length, then circumferentially again on the same side of the armature to a point diametrically opposite, then vertically upward the length of the remainder of the armature, again circumferentially still on the same side of the armature back to the starting point, and so on, thus producing a double 35 armature.

40 In Fig. 6, the winding of the armature is diagonally downward to a point diametrically opposite at the other end of the armature, thence circumferentially on the same side of the armature at a point diametrically opposite and at the same end of the armature, thence diagonally upward again on the same side of the armature to a point diametrically opposite to the point of beginning, and thence, still on the same side of the armature to the starting point, and so on until the winding is completed. The armature winding is thus adapted to set up 55 transverse magnetic fields that are reversed as to polarity near the opposite ends of the armature.

45 The operation of the apparatus is as follows: If no currents flow in the load windings 11 and 12, the currents in the armature 60 winding, in conjunction with the undistorted lines of force of the constant field, produce substantially equal and opposing torques upon opposite ends of the armature,

and the armature, accordingly, remains stationary. However, when currents traverse 65 the load windings 11 and 12, lines of force of the constant magnetic field are shifted so as to cause adjacent polar faces to be of unequal strength, and the opposing torques exerted upon the two ends of the armature are 70 then no longer equal. A resultant torque is thus produced which causes rotation of the armature and which varies as the product of the current in the load windings and the potential current in the armature windings, 75 or in proportion to the watts of the load.

80 As the auxiliary potential coils 10 upon one of the magnet poles are connected to oppose the corresponding load coils and upon the other pole to supplement the corresponding load coils, their arrangement is such that the torques produced by the currents therein, in conjunction with the currents in the armature winding, may oppose and neutralize each other. One of the functions of 85 the auxiliary potential coils is to produce and maintain a difference of magneto motive force between the two faces of each magnet pole. In maintaining this magneto motive force difference the number of turns in 90 the auxiliary potential coils on one magnet pole may be so proportioned that they more than overcome the effects of the residual magnetism in that pole due to the load coils, and the auxiliary potential coils on the other 95 magnet pole may be so proportioned that they assist the residual magnetism. However, the coils that more than overcome the residual magnetism may be of such number of turns as to neutralize the torque due to 100 the residual magnetism. Thus it will be seen that the auxiliary coils may retard the armature to overcome the torque of the armature due to residual magnetism. While 105 the auxiliary coils are primarily for the purpose of maintaining a difference of magneto-motive force and thus actually retard the armature an amount proportional to the torque due to the residual magnetism these 110 coils may be utilized to give a slight resultant torque to the armature to overcome initial friction, this being done by causing the torques resulting from the use of the stationary potential coils, on opposite sides of the armature to be unbalanced. This resultant torque is, of course, proportional to the square of the potential. Another auxiliary 115 resultant torque may also be exerted upon the armature to compensate, either alone or in conjunction with the aforesaid means, for 120 friction, this torque being caused by adjusting the armature longitudinally in order to vary the relative positions of the movable and stationary windings. For instance, the lower portion of the armature winding may 125 be brought partially into the influence of

the upper polar faces of the magnet. This auxiliary torque is substantially proportional to the potential. By causing the auxiliary torque thus produced at a given load to be substantially equal and opposite to the retardation due to friction plus a retarding torque due to the stationary potential coils, which may be produced, as hereinbefore set forth, by slightly unbalancing the torques exerted upon opposite sides of the armature due to said coil, unusually good results are obtainable and the meter will have a high degree of accuracy with variations of potential.

15 The different windings of potential and load are arranged so as to neither add to nor decrease the total field of the constant magnet, so that the armature cup rotates in a constant field regardless of the shifting effects, and, in consequence, the retarding torque varies as the speed, the whole instrument acting as a watt hour meter.

By reason of the fact that the armature is of the two-pole type and the field is also 25 two-pole, there is no tendency for side thrust upon the shaft and bearings, which is an important advantage of the present meter.

To adjust for balance and to compensate 30 for initial friction, the upper portion of the two parts of the core 15 may be elliptically shaped, while the lower portion of the two parts of the core may also be in the shape of an ellipse of the same dimensions as the upper one but with its long axis at right angles to the long axis of the upper one, so that by turning the core, including both parts, any desired adjustment of the upper and lower air gaps relative to each other 40 can be had. This is the equivalent of longitudinally adjusting the armature. A plan view of a core as thus constructed is shown in Fig. 7.

Although, as shown, the load winding is 45 placed on the magnet poles and the main potential winding is on the armature, it should be understood that it may often be desirable to reverse the locations of these windings, in which case the auxiliary potential winding is preferably dispensed with and the requisite amount of potential current is sent through the load winding on the armature by any suitable arrangement of connections, as shown in Fig. 8.

55 It is obvious that the armature may be divided and one part balanced against the other, making virtually two armatures, although electrically, when connected in the same circuit, they would constitute but one.

60 I claim as my invention:

1. A wattmeter comprising a magnet having a substantially constant field, an armature within said field, a winding upon each

pole of the magnet adapted to produce different magnetizing effects opposite different end portions of the armature, and a winding for the armature adapted to produce reverse polarities at opposite ends thereof. 65

2. A wattmeter comprising a magnet having a substantially constant field, an armature within said field, a winding upon each pole of the magnet adapted to produce different magnetizing effects opposite different end portions of the armature, and a winding for the armature adapted to produce reverse polarities at opposite ends thereof, one 70 of said windings being a load winding and the other a potential winding. 75

3. A wattmeter comprising a magnet having a substantially constant field, an armature within said field, a winding upon each pole of the magnet adapted to produce different magnetizing effects opposite different end portions of the armature, and a winding for the armature adapted to produce 80 reverse polarities at opposite ends thereof, and means associated with one of said windings and coöperating with the other to produce an auxiliary driving torque upon the movable member. 90

4. A wattmeter comprising a magnet having a substantially constant field, an armature within said field, a winding upon each pole of the magnet adapted to produce different magnetizing effects opposite different end portions of the armature, and a winding for the armature adapted to produce reverse polarities at opposite ends thereof, one of 95 said windings being a load winding and the other a potential winding, and means associated with the load winding and coöperating with the potential winding to produce an auxiliary driving torque upon the movable member. 100

5. A wattmeter comprising a magnet having a substantially constant field, an armature within said field, a winding upon each pole of the magnet adapted to produce different magnetizing effects opposite different end portions of the armature, and a winding for the armature adapted to produce reverse polarities at opposite ends thereof, and means for adjusting the relative positions of the said windings. 105 110

6. A wattmeter comprising a magnet having a substantially constant field, an armature within said field, a winding upon each pole of the magnet adapted to produce different magnetizing effects opposite different end portions of the armature, and a winding for the armature adapted to produce reverse polarities at opposite ends thereof, and means for adjusting the armature longitudinally in order to vary the relative positions of the said windings. 115 120 125

7. A wattmeter comprising a magnet hav-

ing a substantially constant field, an armature within said field, a winding upon each pole of the magnet adapted to produce different magnetizing effects opposite different 5 end portions of the armature, and a winding for the armature adapted to produce reverse polarities at opposite ends thereof, and an auxiliary winding associated with one of the aforesaid windings and coöperating with 10 the other to produce an auxiliary driving torque upon the movable member.

8. A wattmeter comprising a magnet having a substantially constant field, an armature within said field, a winding upon each 15 pole of the magnet adapted to produce different magnetizing effects opposite different end portions of the armature, and a winding for the armature adapted to produce reverse polarities at opposite ends thereof, and an auxiliary winding associated with but partially opposing one of the aforesaid windings and coöperating with 20 the other to produce an auxiliary driving torque upon the armature.

25 9. A wattmeter comprising a magnet having a substantially constant field, an armature within said field, a winding upon each pole of the magnet adapted to produce different magnetizing effects opposite different 30 end portions of the armature, and a winding for the armature adapted to produce reverse polarities at opposite ends thereof, an auxiliary winding associated with but partially opposing different portions of one of 35 the aforesaid windings and coöperating with the other to produce an auxiliary driving torque upon the armature, and a shunt for the said auxiliary winding.

40 10. A wattmeter comprising a magnet having a substantially constant field, an armature within said field, a winding upon each pole of the magnet adapted to produce different magnetizing effects opposite different end portions of the armature, and a 45 winding for the armature adapted to produce reverse polarities at opposite ends thereof, one of said windings being a load winding and the other a potential winding, and an auxiliary potential winding associated with but partially opposing the load 50 winding and coöperating with the other potential winding to produce an auxiliary driving torque upon the armature.

55 11. A wattmeter comprising a magnet having a substantially constant field, an armature within said field, a winding upon each pole of the magnet adapted to produce different magnetizing effects opposite different end portions of the armature, and a 60 winding for the armature adapted to produce reverse polarities at opposite ends thereof, one of said windings being a load winding and the other a potential winding,

an auxiliary potential winding associated with the load winding but partially opposing different portions thereof and coöperating with the other potential winding to produce an auxiliary driving torque upon the armature, and a shunt for the said auxiliary winding. 65 70

12. A wattmeter comprising a magnet having a substantially constant field, an armature within said field, a winding upon each pole of the magnet adapted to produce different magnetizing effects opposite different end portions of the armature, and a winding for the armature adapted to produce reverse polarities at opposite ends thereof, and an auxiliary winding associated with one of the aforesaid windings, 80 and an adjustable shunt to the said auxiliary winding.

13. A wattmeter comprising a magnet having a substantially constant field, an armature within said field, a winding upon each pole of the magnet adapted to produce different magnetizing effects opposite different end portions of the armature, and a winding for the armature adapted to produce reverse polarities at opposite ends 90 thereof. 85

14. A meter comprising a magnet having a substantially constant field and two sets of opposite polar faces, and an armature rotatably mounted between the polar faces, 95 the two sets of polar faces being respectively adjacent to different end portions of the armature.

15. A meter comprising a magnet having a substantially constant field, and two sets 100 of opposite polar faces, an armature rotatably mounted between the polar faces, the two sets of polar faces being respectively adjacent to different end portions of the armature, and a winding upon each polar projection, those upon adjacent projections having opposite magnetizing effects. 105

16. A meter comprising a magnet having a substantially constant field, and an armature rotatably mounted between the poles of 110 the magnet, each of said poles having two divisions that respectively oppose different end portions of the armature.

17. A meter comprising a magnet having a substantially constant field, each pole of 115 which has two divisions, a winding upon each polar division, an armature between the magnet poles having its end portions disposed respectively opposite different divisions of each magnet pole. 120

18. A meter comprising a magnet having a substantially constant field and two sets of opposing polar projections arranged axially side by side and an armature having a winding that produces reverse polarities at 125 its opposite ends.

19. A meter comprising a two-pole magnet having a substantially constant field and a pair of pole faces for each pole, and an armature having a double two-pole winding. to be exerted upon the movable member approximately proportional to the square of potential.
- 5 20. A meter comprising a two-pole magnet having a substantially constant field and a pair of pole faces for each pole, and an armature having a double two-pole winding, the polarities of the two portions of 60 which are reversed with respect to each other.
- 15 21. A meter comprising a two-pole magnet having a substantially constant field and a pair of pole faces for each pole, a winding for each polar portion thereof, and an armature having a double two-pole winding. 65
- 20 22. A meter comprising a two-pole magnet having a substantially constant field and a pair of pole faces for each pole, and an armature having a double two-pole winding, the polarities of the two portions of which are reversed with respect to each other. 70
- 25 23. A meter comprising a permanent magnet having divided poles, a winding upon each polar division, and an armature, the divisions of each magnet pole being presented to different portions of the armature. 75
- 30 24. A meter comprising a magnet having a substantially constant field, windings respectively upon the different portions of each pole of the magnet, and an armature, the windings carried by portions of each magnet pole being opposite different portions of the armature relative to its length. 80
- 35 25. In a wattmeter, the combination with a movable member, and means coöperating therewith whereby a main torque is exerted thereon approximately proportional to the product of potential and current, and also 85
- 40 a supplementary torque that is approximately proportional to potential, of means also coöperating with the said movable member for causing another auxiliary torque to be exerted upon the movable member approximately proportional to the square of potential. 90
- 45 26. In a wattmeter, the combination with a movable member, and means coöperating therewith whereby a main torque is exerted thereon approximately proportional to the product of potential and current, and also a supplementary torque that is approximately proportional to potential, of means also coöperating with the said movable member for causing an auxiliary retarding torque 95
- 50 the polarities of the two portions of which are reversed with respect to each other. 100
- 55 In testimony whereof, I have hereunto subscribed my name this 17th day of March, 1911.

THOMAS W. VARLEY.
